CLAIM

The ornamental design for a drug delivery device, substantially as shown and described.

DESCRIPTION

The patent or application file contains at least one drawing executed in color. Copies of this patent or patent publication with color drawings(s) will be provided by the Office upon request and payment of the necessary fee.

FIG. 1 is a rear view of the drug delivery device;

FIG. 2 is a front view thereof;

FIG. 3 is a right side view thereof;

FIG. 4 is a left side view thereof;

FIG. 5 is a bottom view thereof;

FIG. 6 is a top view thereof; and,

FIG. 7 is a perspective view thereof.

“Pen-shaped Injection Device” (with cap, expanded number sleeve, as colored photograph) (Pantone codes: body Q030-3-1, dial grip 155C, dose button 144C).

1 Claim, 7 Drawing Sheets
(7 of 7 Drawing Sheet(s) Filed in Color)
